UNITED STATES PATENT OFFICE.

WILLIAM H. NELSON, OF HAZLETON, IOWA.

EXTENSION-TRESTLE.

SPECIFICATION forming part of Letters Patent No. 651,444, dated June 12, 1900.

Application filed March 16, 1900. Serial No. 8,897. (No model.)

To all whom it may concern:

Be it known that I, WILLIAM H. NELSON, a citizen of the United States of America, and a resident of Hazleton, Buchanan county, and 5 State of Iowa, have invented certain new and useful Improvements in Extension-Trestles, of which the following is a specification.

My invention relates to improvements in extension-trestles; and the object of my improvement is, first, to provide means whereby when workmen have once ascended the trestle they may elevate it to different heights without incurring the necessity of descending for that purpose, and, second, to provide other 15 means for increasing the height of trestle when it has otherwise reached its capacity for extension. I attain these objects by the means which are illustrated in the accompanying drawings, in which—

20 Figure 1 is a side elevation of the trestle as partly extended, having a portion of the frame bars and legs removed in order to show the pulleys and cables. Fig. 2 is an end elevation of the trestle, showing it partly extended, but unprovided with the extension-legs; and 25 Fig. 3 shows a leg of the trestle as seen from the end, having an extension-leg attached.

Similar letters refer to similar parts throughout the several views.

30 As is illustrated, *a* represents the upper or cross bar of an extension-trestle, supported at either end by the standards *k* and *k'*.

b and *b'* are frame-bars supported at points near their ends by the posts or legs *n* and *n'* 35 and *r* and *r'*. The legs *n* and *n'* and *r* and *r'* are connected to the frame-bars *b* and *b'* by means of bolts, as at *z*, which latter are furnished with nuts, as at *z'*, for compressing the parts together.

40 In the longitudinal space between the frame-bars *b* and *b'* are placed the pulleys *s* and *w* and rollers *t* and *v*, which move in bearings in the frame-bars. The lower part of the standard *k* is also provided with an opening 45 extending from front to rear, in which is placed the pulley *x*. Through the end of the cross-bar *a*, outside the standard *k*, a shaft *c* is passed perpendicularly and is retained vertically in position by being passed through an opening 50 in the brace *g*, which latter is affixed to the lower part of the standard *k*. The shaft *c* is operated by means of a hand-lever *d* at its

top, and is retained in position by the ratchet-wheel *e* and dog *f*.

The standards *k* and *k'* move between the 55 guides *l* and *l'* and *m* and *m'*, respectively, and the legs *n* and *n'* are connected and braced by the beam *y*, as are also the legs *r* and *r'* by a similar beam.

To the shaft *c*, at a point below the brace *g*, 60 is attached a cable *h*, which is arranged to wind about it, and thence around the pulley *x* in the standard *k*. This cable after passing around this pulley is conducted upward and fastened to a bolt (not here shown) running 65 across from the frame-bar *b* to the frame-bar *b'*.

If desired, the cable *h* may be attached to and wound about the shaft *c* at any point above the brace *g* instead of below it. 70

u is a cable fastened at the point *u'* to the forward under part of the cross-bar *a*. This cable is then passed under and about the pulley *s* and the roller *t*, thence upward and about the roller *v* and pulley *w*, and thence downward to the lower part of the standard *k'*, 75 where it is fastened at the point *u''*.

The extension-legs *o*, *o'*, &c., are, when it is thought necessary to add to the height of the trestle, connected to the lower ends of the 80 legs *n*, *n'*, *r*, *r'* by means of the retaining-rings, such as are shown in Fig. 3 at *p'* and *q'*. These rings are affixed to the extensions, and the lower rings have caps over the under part to form sockets for the reception of the legs of 85 trestle.

The trestle is extended in the following manner: The shaft *c* is rotated by means of the hand-bar *d*, the ratchet and dog keeping it in the position it assumed when released. 90 The revolution of the shaft *c* causes the cable *h* to become wound about it, and the cable passing around the pulley *x* elevates the standard *k* with the cross-bar *a*. In order to cause a simultaneous elevation of both 95 standards *k* and *k'* and to obviate cramping of the parts, the cable *u* is employed. As the cross-bar *a* rises it draws with it the cable *u* from the point where it is attached at *u'*. This cable, moving about the pulley *s* and roller *t* 100 and the roller *v* and pulley *w*, draws upward the lower part of the standard *k'* simultaneously with the elevation of the standard *k*. If when the cross-bar *a* has been thus raised

to any desired height it is thought best to keep it in that position for any certain time, the nuts on the bolts connecting the frame-bars *b* and *b'* are tightened up, as at *s'*, thus compressing the pulleys *s* and *w* between the bars and preventing their revolution. The cross-bar *a* may be readily lowered on releasing the dog *f* from its engagement with the ratchet-wheel *e*. When the limit of extension of the trestle is reached, it may be increased in height by connecting to its legs the extensions *o o'*, &c. This is done by slipping the upper rings of the extensions over the legs and then allowing the lower ends of the legs to settle into the sockets of the lower rings.

The trestle may be readily separated for packing by removing the bolts connecting the frame-bars.

It will be seen that by the use of the means illustrated it becomes unnecessary for a workman to descend and reascend from his staging, but may elevate or depress it from the top while standing upon it.

Having described my invention, what I claim as new, and desire to secure by Letters Patent of the United States, is—

1. In an extension-trestle, the combination of the cross-bar *a*, standards *k* and *k'*, frame-bars *b* and *b'*, pulleys *x*, *s* and *w*, rollers *t* and *v*, legs *n*, *n'*, *r* and *r'*, bolts *z* secured by nuts *z'*, slideways *l* and *l'*, *m* and *m'*, brace *g*, the shaft *c* provided with the ratchet-wheel *e* and dog *f* and hand-lever *d*, with the cables *h* and *u*, all suitably connected and supported, substantially as shown and described. 30

2. In an extension-trestle, the combination of the cross-bar *a*, standards *k* and *k'*, frame-bars *b* and *b'*, pulleys *x*, *s* and *w*, rollers *t* and *v*, legs *n*, *n'*, *r*, *r'*, bolts *z* secured by nuts *z'*, slideways *l* and *l'*, *m* and *m'*, brace *g*, shaft *c* 40 provided with ratchet-wheel *e* and dog *f* and hand-bar *d*, cables *h* and *u*, with the extension-legs *o*, *o'*, &c., provided with retaining-rings *p* and *q*', &c., all suitably connected and supported, substantially as shown and 45 described.

Signed by me at Hazleton, Buchanan county, Iowa, this 12th day March, 1900.

WILLIAM H. NELSON.
